VERTICAL UNIT HEATER

Clifford C. Carson, Chicago, Ill.

Application May 31, 1930, Serial No. 458,299

11 Claims. (Cl. 257—137)

This invention relates to unit heaters of the type especially adapted for heating factory buildings and the like and, among other objects, aims to provide an improved vertical, suspension type heater having provision for discharging a confining curtain or stream of air above the heated air so as to prevent the heated air from rising above the breathing line before it gives up a substantial portion of its heat.

10 This application is intimately related to my co-pending application, Ser. No. 458,300, filed May 31, 1930, and also involves the method broadly claimed in my co-pending application, Ser. No. 308,681, filed Sept. 27, 1928, which has matured into Patent No. 1,820,893 granted Aug. 25, 1931. One of the important features of this invention is the vertical arrangement of the suspended heater casing whereby the intake air is taken from the upper part of the room or building where the temperature is higher than is the temperature near the floor level. Moreover, the temperature of the confining stream or curtain of high velocity air is maintained at a somewhat higher temperature than would be maintained if the intake air were admitted near the floor level. Furthermore, the arrangement is such that room air will circulate upwardly through the casing in the event that the fan is stopped and thereby set up a natural circulation of the air.

20 Other aims and advantages of the invention will appear in the specification, when considered in connection with the accompanying drawings, wherein:

35 Fig. 1 is a side elevation, partly in section, showing a suspension heater embodying the invention;

Fig. 2 is a bottom plan view; and

Fig. 3 is a sectional view taken on the line 40 3—3 of Fig. 1.

Referring particularly to the drawings, the heater there shown is similar in many respects to that shown in my aforesaid application, Ser. No. 458,300, filed May 31, 1930. It is adapted to be suspended from roof joists or supported on columns at any desired height above the floor where it does not take up any valuable floor space and is adapted to heat the building or room very largely by displacement hot air currents discharged into the working zone or below the breathing line.

In this example, the heater is shown as being mounted in a vertical rectangular casing 10 made of sheet metal and having an open upper end. One or more centrifugal fans 11 carried

on a shaft 12 journaled in opposite sides of the casing are arranged in the upper open end so as to take air from the upper portion of the building or room and blow it downwardly through the casing to be heated. Herein, three fans 11 are mounted in spaced housings 13 each having a double scroll. From each fan housing air is delivered through a discharge outlet 14 into the heater casing and a small discharge duct 15 connected to a vertical by-pass conduit 16 arranged adjacent to the front wall of the casing. The arrangement is such that the air delivered through the by-pass conduits is not heated and travels at a much higher velocity than the currents of air delivered through the casing.

Referring to Fig. 1, intake air is admitted to the respective fans through ordinary inlet cones 17 in the opposite end walls of the fan housings so that air is sucked into the fans practically throughout the open end of the heater casing. In this instance, the fan shaft 12 projects through one side wall of the casing 10 and is driven by a motor 18 supported on a suitable bracket or shelf 19 which is conveniently secured to the outside wall of the casing.

Referring to Fig. 3, the casing 10 is shown as having a transverse horizontal partition 20 to which the fan discharge ducts or outlets 14 are connected to deliver air into a heating chamber or compartment 21. The lower end of the casing 30 has an end wall 22 and a vertical partition 23 is shown as being connected to the partition 20 and the end wall 22 providing the front wall of the heating chamber. This construction provides an insulating, dead air chamber housing the by-pass conduits 16 so that the relatively cold air passing through them will not absorb heat from the heating chamber.

Within the heating chamber 21 there is shown an ordinary tubular heater unit 24 such as is usually heated by steam or hot water; but it is to be understood that the source of heat is a matter of selection. Obviously, a direct fired heater utilizing fluid fuel may be employed. In any event, the arrangement is such that the air passing 45 through the chamber is raised to the desired temperature before it is discharged into the space to be heated.

Further referring to Fig. 3, the heated air is discharged downwardly from the lower end of the heating chamber through discharge conduits 25 directed at an angle to the horizontal, the inclination depending on the size of the building and the height of the discharge orifices above the floor. Herein, they are inclined at approximate- 55

ly 45° merely for illustration purposes. Each conduit preferably has a division plate or partition 26 to direct the air at a substantially constant velocity throughout the height of the outlet orifice; otherwise, the air would discharge at the greatest velocity near the bottom of the outlet orifice. The by-passed relatively cold air is discharged through wide flat nozzles 27 connected to the lower ends of the conduits 16 and preferably arranged immediately above the conduits 25 so as to discharge curtains of air at high velocities substantially parallel with the issuing streams of hot air. The velocity ratios depend upon the size of the building and other variable factors. In some instances, the ratio should be about two to one.

As disclosed in my aforesaid application, Ser. No. 458,300, filed May 31, 1930, the nozzles 27 preferably have adjustable Venturi blades 28 in their mouths so as to vary the angle of discharge and prevent the curtain streams from spreading vertically. The idea is to so regulate the velocity and direction of discharge of the curtain streams as to cause them to flatten out horizontally at or near the breathing line and prevent penetration of the heated air before it gives up a substantial portion of its heat below the breathing line. Without the confining stream or streams of air, the induced air currents set up at the intake end of the heater casing would promote rapid rise of the hot air by setting up continuous circulation from the discharge end back toward the intake end.

While the Venturi vanes 28 may be adjusted to restrict the flow of air through the nozzles 27, an adjustable damper 29 is shown in each of the cold air conduits 15 so that the volume and velocity of the air passing through the conduits may be widely varied to suit the particular requirements. Thus, the temperature difference and relative velocities of the hot and cold air streams may be changed at will. Hence, a heater of this type may be quickly adjusted to operate economically in any ordinary building or room.

From the foregoing description, it will be seen that unit heaters embodying this invention can be manufactured very economically and installed very quickly. They are very compact in design and are far more efficient than the old and well known types of suspended heaters. The high velocity streams of air produce more uniform distribution of the heated air and maintain approximately constant temperatures of wide areas. Moreover, this type of heater will reduce the normal temperature rise per foot of height and thus reduce the normal heat losses through the roof of a building.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. A unit heater of the class described comprising, in combination, a substantially vertical, rectangular casing having an open upper end; a heating chamber in the lower portion of the casing; a heat exchanger in the heating chamber; a plurality of fans in the open end of said casing and connected to deliver air through said chamber; a plurality of hot air discharge conduits, one for each fan, at the lower end of said casing arranged to direct the air downwardly at

an angle to the horizontal into the space to be heated; and means to deliver a separated curtain of relatively cold air at high velocity above the discharging hot air.

2. A unit heater of the class described comprising, in combination, a substantially vertical rectangular casing having an upper open end; a heating chamber in the lower portion of the casing; a heat exchanger in the heating chamber; a plurality of fans in the open end of said casing and connected to deliver air through said chamber; a plurality of hot air discharge conduits, one for each fan, at the lower end of said casing arranged to direct the air at an angle to the horizontal; by-pass conduits connected to said fans; and nozzles at the ends of said by-pass conduits arranged to discharge curtains of air at high velocity above the discharging hot air.

3. A unit heater of the suspension type comprising, in combination, a substantially vertical casing; a heating chamber in the lower portion of said casing; heating means in said chamber; a plurality of centrifugal fans adjacent to the upper end of the casing having discharge outlets connected to said heating chamber; a plurality of hot air discharge outlets, one for each fan, connected to the lower end of said casing and shaped to direct the air at an angle to the horizontal; by-pass conduits connected to said fans and passing through said casing at one side of the heating chamber; and relatively wide discharge nozzles at the lower ends of said by-pass conduits adjacent to said hot air conduits adapted to discharge curtains of relatively cold air at high velocity above and substantially parallel with the discharging hot air.

4. A unit heater of the class described comprising, in combination, a substantially vertical casing having an open upper end and a heating chamber in its lower end portion; a tubular heat exchanger in said heating chamber; means in the open end of said casing to create a blast of air through said heating chamber; a discharge conduit for the heated air at the lower end of said casing connected to direct the air downwardly at an angle to the horizontal; and means to discharge a separate stream of relatively cool air adjacent to the discharging hot air whereby to confine the hot air to circulate in the lower portion of the space to be heated until it has given up a substantial portion of its heat.

5. A unit heater of the class described comprising, in combination, a substantially vertical casing; means to suspend the casing above the space to be heated; a heating chamber within the casing; a tubular heat exchanger within the chamber; a plurality of centrifugal fans adjacent to the upper end of said casing and connected to discharge air through said heating chamber; a motor supported on said casing and connected to drive all of said fans; a plurality of hot air discharge conduits, one for each fan, connected to the lower end of said casing and arranged to direct the hot air at an angle to the horizontal; by-pass conduits connected to said fans and passing through the casing on the outside of said heating chamber; relatively flat nozzles connected to said by-pass conduits adjacent to the hot air discharge conduits; adjustable Venturi vanes in the mouths of said nozzles; and means to vary the volume of air passing through said by-pass conduits.

6. A unit heater of the class described, comprising, in combination, a substantially vertical casing; means to support the casing above the

space to be heated; a horizontal partition within the casing below the upper end thereof and providing a heating chamber in the lower portion of the casing; a plurality of centrifugal fans arranged adjacent to the upper end of the casing; outlet conduits for the fans connected to said partition and discharging into the heating chamber; a heat exchanger mounted in said heating chamber; a plurality of hot air discharge conduits, one for each fan, connected to the lower end of said casing and arranged to discharge hot air at an angle to the horizontal; by-pass conduits connected to said fans and arranged to deliver air at a relatively high velocity; and a plurality of relatively wide discharge nozzles connected to said by-pass conduits adjacent to the hot air conduits and arranged to discharge confining curtains of relatively cold air at high velocity above the discharging hot air whereby to confine the hot air to circulate in the lower portion of the space to be heated until it has given up a substantial portion of its heat.

7. A unit heater of the suspension type comprising, in combination, a casing, heating means within the casing; a fan connected to create a current of air through the casing; a conduit connected to the fan and arranged to by-pass a portion of the air at a relatively high velocity around the heating means; a hot air discharge conduit connected to the casing and directed downwardly at an angle to the horizontal; and a discharge nozzle for the by-passed air above the hot air discharge conduit arranged to discharge a confining stream of air above the hot air.

8. A unit heater of the suspension type comprising, in combination, a casing, heating means within the casing; a fan connected to create a current of air through the casing; a conduit connected to the fan and arranged to by-pass a portion of the air at a relatively high velocity around the heating means; a hot air discharge conduit connected to the casing and directed downwardly at an angle to the horizontal; and

a discharge conduit for the by-passed air above and adjacent to the hot air conduit and shaped to discharge a relatively thin curtain of air at high velocity above the discharging heated air so as to confine the heated air to circulate in the lower portion of the space to be heated until it gives up a substantial portion of its heat.

5

9. A unit heater of the suspension type comprising, in combination, a casing; heating means within the casing; a fan connected to create a current of air through the casing; a conduit connected to the fan and arranged to by-pass a portion of the air at a relatively high velocity around the heating means; a hot air discharge conduit connected to the casing and directed downwardly at an angle to the horizontal; and a wide relatively flat nozzle connected to the by-pass conduit above the hot air discharge conduit and adapted to discharge a confining curtain of air at high velocity above the hot air.

20

10. A unit heater of the suspension type comprising, in combination, a casing; tubular heat exchanging elements within the casing; a fan connected to create a current of air through the casing; a conduit connected to the fan and arranged to by-pass a portion of the air at a relatively high velocity around the heat exchanging elements; a hot air discharge conduit connected to the casing and directed downwardly at an angle to the horizontal; and a discharge nozzle for the by-passed air above the hot air discharge conduit arranged to discharge a confining stream of air above the hot air.

25

11. A unit heater of the class described comprising, in combination, an elongated substantially rectangular casing open at one end; a centrifugal fan supported in the open end and connected to discharge through the casing; heating means near the other end of the casing; a discharge conduit for the heated air; a wide discharge nozzle above the hot air conduit; and means to deliver air at a relatively high velocity through said nozzle.
